US00D795193S

(12) **United States Design Patent** (10) **Patent No.:** **US D795,193 S**
(45) **Date of Patent:** **** Aug. 22, 2017**

(54) **AC COUPLER OF ELECTRIC VEHICLES**(71) Applicant: **Suzhou Recodeal Interconnect System Co.,Ltd.**, Suzhou (CN)(72) Inventor: **Yingde Huang**, Suzhou (CN)(**) Term: **15 Years**(21) Appl. No.: **29/548,833**(22) Filed: **Dec. 17, 2015**(51) LOC (10) Cl. **13-03**

(52) U.S. Cl.

USPC ..... **D13/133**(58) **Field of Classification Search**

USPC D13/118, 123, 133-135, 145-147, 149, D13/151, 173, 184, 199

CPC B60L 11/18; H01R 13/00; H01R 13/18; H01R 13/33; H01R 13/40; H01R 13/52; H01R 13/56; H01R 13/58; H01R 13/62; H01R 13/63; H01R 24/00; H01R 33/00; H02J 7/00

See application file for complete search history.

Primary Examiner — Thomas Johannes*Assistant Examiner* — Shawn T Gingrich(74) *Attorney, Agent, or Firm* — Wayne & Ken, LLC; Tony C. Hom(57) **CLAIM**

The ornamental design for AC coupler of electric vehicles, as shown and described.

DESCRIPTION

FIG. 1 is perspective view showing my design;

FIG. 2 is a front view showing my design;

FIG. 3 is a back view showing my design;

FIG. 4 is a left side view showing my design;

FIG. 5 is a right side view showing my design;

FIG. 6 is a top plan view showing my design; and,

FIG. 7 is a bottom plan view showing my design.

1 Claim, 7 Drawing Sheets(56)
